CHIMNEY SUPPORT AND CHIMNEY FOR INCANDESCENT BURNER

Carl Bramming, Nashville, Tenn., assignor to Aladdin Industries, Incorporated, Nashville, Tenn., a corporation of Illinois

Application November 1, 1952, Serial No. 318,193

2 Claims. (Cl. 240—99)

This invention relates to chimneys for incandescent mantle lamp burners, and more particularly to novel complementary chimney supporting means defined partly by the base portion of the chimney and partly by elements secured to the gallery of the burner.

The chimneys used on incandescent mantle lamps, and their supporting means, have included many shapes and forms developed to solve the problem of attaching a clear glass chimney to a metal base in such a way as to have the chimney selectively removable from the base, but not inadvertently removable therefrom. These earlier chimney mountings and shapes have included, subsequent to the early perforated mounting ring and perfectly circular chimney, various locking and cam devices provided to furnish a connection which is substantially permanent unless intentionally disengaged. A principal source of difficulty with these prior devices has been that the cam action required has exceeded the distortion capabilities of the glass, resulting in broken chimneys, or the glass has been stressed in such a manner that repeated heatings and coolings will accelerate its crystallization and subsequent failure.

It is necessary, in obtaining maximum efficiency in incandescent mantle lamps, to provide sufficient secondary air to obtain substantially complete combustion and to permit adequate cooling of the gallery and of the burner parts. If the burner becomes overheated the flow of fuel through the wick increases to such an extent that the fuel runs down along the wick tubes. However, it is not desirable to admit too much air to the burner between the chimney and the gallery because an excessively large air gap permits drafts and air currents to blow out the flame. Consequently the normal galleries are provided with an outer ring supporting the chimney with a narrow air gap therebetween. This construction results in intimate contact between the chimney and the gallery over a large surface area and frequently leads to the increased flow of fuel referred to above.

It is therefore an object of this invention to provide a chimney mounting structure having minimum contact with both the chimney and the gallery part of an incandescent burner.

A further object is to provide a chimney mounting structure which offers maximum permissible air passage from outside the lower part of the chimney into the combustion area of the burner.

A further object is to provide a chimney having its lower end shaped to cooperate with the new chimney mounting structure, and so formed as to permit the locking of the chimney on the body of the burner without unduly stressing the chimney or the mounting structure.

Further objects and advantages will be apparent from a study of the following description in connection with the accompanying drawings in which,

Fig. 1 is an elevational view, partially in section, showing the new chimney and chimney mounting structure,

Fig. 2 is a view in horizontal section through the lower

2

flange of the gallery body upon which the chimney supports are mounted, with the supports shown in full line, Fig. 3 is a detail vertical sectional view of a portion of the chimney,

Fig. 4 is a view in section on the line 4—4 of Fig. 3, Fig. 5 is a view in section on the line 5—5 of Fig. 3, and Fig. 6 is a view in section on the line 6—6 of Fig. 3. In the drawings the incandescent lamp 10 is indicated as having an outer wick tube 11 mounted in a suitable support 12 and having its wick 13 extending into a fuel reservoir. Supported from the outer wick tube 11, by suitable means, is a gallery body 14 having a lower flange 15 and a crown 16.

Fig. 1 also shows a mantle 17 supported by a yoke 18 which is cemented as at 19 to a cross-wire 20, supported from a pair of substantially parallel arms 21, which are in turn received in sockets 22 defined by the gallery body 14. A mantle ring 23 is attached by means of the ears 24 to the arms 21, at a point adjacent the lower end of the mantle 17. The lamp and mantle mounting are disclosed in my copending application Serial No. 318,194, filed Nov. 1, 1952.

The chimney supporting structure comprises three supporting clips 25 mounted at 120° to each other and supported by the lower flange 15 of the gallery body 14. Each clip 25 has a substantially vertical mounting plate 26, a horizontal base 27, and an upstanding cam follower edge 28. Above the mounting face 26 there is positioned a retaining arm 29 which is shaped to permit easy rotation of a chimney 30 in the mounting structure.

It is to be noted, especially from Fig. 2, that the mounting devices 25 are fairly small and take up little of the annular air passage area available. This permits maximum air movement between the gallery body 14 and the chimney 30.

The chimney 30 is of conventional structure down to a point a short distance above its base. The portion of the chimney detailed in Figs. 3, 4, 5 and 6 is unconventional and provides cam-acting and locking means adapted for use with the chimney support devices 25.

The lower portion of the chimney 30 is formed with three inwardly projecting retaining beads 31 adapted to coact with the retaining arm 29 when the body of the chimney 30 is assembled into proper engagement with the support members 25. The beads 31 are equally spaced and extend along arcs of about 90°. They are separated by entrance channels 32 which are approximately 30 degrees in width and are also 120 degrees apart. These entrance channels 32 provide spaces which permit the passage of the retaining arms 29 a sufficient distance into the chimney 30 to permit the chimney then to be rotated so that the beads 31 will underlie the arms 29. Three stop dimples 33 are also pressed into the wall of the chimney 30 immediately above the respective retaining beads 31. With this construction the chimney may be slipped over the outside of the three mounting devices 25 and bottomed on the base plate 27 thereof without in any way distorting the chimney or stressing the retainer arms 29. Then, as the chimney is rotated to lock the beads 31 in position under the arms 29, the stop dimples 33 are engaged by the arms 29 when the preferred position is obtained, without stressing the chimney or distorting the retainer arm 29.

A plurality of locking cams 34 are provided at the lowermost extremity of the chimney 30. The cams 34 are constituted by three areas in which the side walls of the chimney 30 are distorted outwardly, with the center point of each cam 34 positioned approximately centrally between the mid-point of the stop dimple 33 and the near edge of the related entrance passage 32.

When the chimney 30 is assembled as above described, and rotated, the cam surfaces 34 will be engaged by the

cam follower faces 28. Rotation of the chimney 30, by reason of this engagement and camming action, will center the chimney 30 with respect to the mounting devices 25 and position the retainer beads 31 in proper alignment with respect to the retainer arms 29. Rotation of the chimney 30 is sufficient, prior to the engagement of the stop dimple with the retaining arm 29, to permit the center of the cam 34 to pass beyond the center of the cam follower 28. This will provide a locking of the chimney in the desired position.

Having described my invention what I desire to protect by Letters Patent and claim is:

1. In a fuel burning lamp having a burner thereon, the combination comprising an annular supporting member adapted to be mounted on the burner, a plurality of angularly spaced chimney supporting clips mounted on said annular member at equal angular intervals around the periphery thereof, each of said clips being formed of flat sheet material and being of generally U-shaped form, each of said clips including a flat horizontal portion disposed in a transverse radial plane, each of said clips having opposed inner and outer fingers projecting upwardly from said horizontal portion in radially spaced-apart relation, each of said inner fingers having a lug portion at its upper end projecting radially outwardly, a chimney detachably mounted on said clips, said chimney being generally tubular and open-ended in form, said chimney having a generally cylindrical lower wall portion with an annular lower edge engaging said horizontal portions of said clips, said lower wall portion having a plurality of substantially horizontal arcuate inwardly projecting ridges spaced around the inside of said lower wall portion at equal angular intervals, said ridges corresponding in number and in angular disposition to said clips, said lower wall portion having arcuate substantially cylindrical entrance elements disposed between said ridges for passing said lugs on said inner fingers, said chimney being rotatable on said clips between a released position with said entrance elements aligned with said inner fingers to permit upward withdrawal of said chimney and a locked position angularly displaced in one direction from said released position with said lugs on said inner fingers disposed above said ridges and engaged therewith in interlocking relation, said lower wall portion having a plurality of inwardly projecting stop elements disposed along said ridges and engaging said inner fingers with said chimney in said locked position to define said locked position and prevent rotation of said chimney beyond said locked position, said lower wall portion having a plurality of outwardly projecting cam locking lobes corresponding in number and angular spacing to said clips, said locking lobes projecting outwardly to a circle of a diameter at least as great as that of a circle encompassing the insides of said outer fingers, said lobes being positioned angularly between said entrance elements and said stop elements so that said lobes will pass said outer fingers

in the course of rotation of said chimney between said released and said locked positions, said lobes engaging said outer fingers in said locked position and resisting counter rotation of said chimney to said released position.

2. In a chimney for a burner having a plurality of U-shaped chimney supporting clips thereon, each with a base portion, an outer finger projecting upwardly from the outer edge of said base portion, and an inner finger 10 projecting upwardly from said base portion in inwardly spaced relation to said outer finger and having an outwardly projecting lug at the upper end of said inner finger, the combination comprising a generally tubular open-ended body having a generally cylindrical lower wall portion terminating in a downwardly facing annular edge 15 adapted to engage and be supported on the base portions of the clips, said lower wall portion having a plurality of arcuate inwardly projecting ridges spaced above said lower edge and extending substantially parallel thereon to along the inside of said lower wall portion at equal angular intervals, said lower wall portion having arcuate, substantially cylindrical entrance elements disposed between said ridges for passing said lugs on said inner fingers, said chimney being receivable on the clips and 20 being rotatable between a released position with said entrance elements aligned with the inner fingers to permit insertion and withdrawal of said chimney and a locked position angularly displaced in one direction from said released position with the lugs on the inner fingers disposed above said ridges and engaged therewith in interlocking relation, said lower wall portion having a plurality of inwardly projecting stop elements disposed along said ridges in angularly spaced relation to said entrance 25 elements for engaging the inner fingers with said chimney in said locked position to prevent rotation of said chimney beyond said locked position, said lower wall portion having a plurality of outwardly projecting cam lobes spaced at equal angular intervals around the outer periphery thereof for engaging the outer fingers on the clips, said 30 lobes being oriented angularly between said entrance elements and said stop elements so that said lobes will be moved over-center beyond their positions of alignment with the outer fingers in rotating the chimney into said locked position with the inner fingers engaging said stop elements, said cam lobes thereby resisting counter rotation of said chimney to said released position.
